The ornamental design for a spoon-shaped mashing utensil, as shown and described.

DESCRIPTION

FIG. 1 is a front perspective view of a spoon-shaped mashing utensil showing our new design.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof; and,

FIG. 7 bottom plan view thereof.

The broken lines in the figures are for illustrative purposes only and form no part of the claimed design.
